UNITED STATES PATENT OFFICE.

BRUCE S. ELLIOTT, OF ST. LOUIS, MISSOURI, ASSIGNOR TO ALSOP PROCESS COMPANY,
OF ST. LOUIS, MISSOURI, A CORPORATION OF MISSOURI.

COTTON EXTRACTING AND CLEANING MACHINE.

1,081,594.

Specification of Letters Patent. Patented Dec. 16, 1913.

Application filed December 23, 1912. Serial No. 738,115.

To all whom it may concern:

Be it known that I, BRUCE S. ELLIOTT, a citizen of the United States, residing in the city of St. Louis and State of Missouri, have 5 invented new and useful Improvements in Cotton Extracting and Cleaning Machines, of which the following is a specification.

This invention relates to cotton extracting and cleaning machines, and has for its object 10 improvements in the machine heretofore patented to John E. Mitchell, No. 1,030,913, dated July 2nd, 1912. The present invention is, in effect, supplemental to two applications of John E. Mitchell filed of even 15 date herewith, wherein is disclosed the idea of forcibly projecting cotton at the bottom of a hull board into contact with a saw cylinder, one of said applications showing a vibratory, and the other a reciprocatory, 20 hull board as means of accomplishing such object. In the present invention the same principle of operation is retained, but is carried out by means of an air blast discharged from the lower end of the hull 25 board whereby the cotton passing to such lower end is blown over against the saw cylinder while the hull particles are permitted to fall through the opening provided 30 between the edge of the hull board and said saw cylinder.

In the accompanying drawing the figure 35 illustrates a central cross sectional view through a machine of the Mitchell type having my invention applied thereto.

Referring now to the drawing, the casing 1, feed rolls 2, boll crushing cylinder 3, saw cylinder 4, pod expeller 5, supplemental crushing roll 6, guard 7, doffer-brush 8, and conveyer 9 are constructed and arranged as 40 fully illustrated and described in the patent of Mitchell aforesaid, or in his applications filed of even date herewith, and as they form no part of my invention they need not be more fully described herein.

The numeral 10 indicates my improved 45 hull board which is secured at its upper end to a cross bar 11 supporting one end of the screen 12 which surrounds the boll crushing cylinder 3. This hull board is made hollow 50 and is preferably, though not necessarily, constructed of sheet metal. The upper surface of this hull board is provided toward its lower end with an inclined portion 13 extending at a less angle to the saw cylinder 55 than the upper portion 14 of said hull board

whereby a shoulder 15 is provided which prevents the unopened bolls and larger pieces of hull from passing into the space between the end portion 13 and the saw cylinder. The lower end portion of the hull 60 board as a whole is contracted in area, and along its bottom edge, facing the saw cylinder, is provided with a discharge nozzle 16 provided with a relatively narrow slot 17 for permitting a blast of air to be directed toward the saw cylinder. 65

The numeral 18 indicates a fan which is run by a belt 19 from a pulley 20, which is on the shaft 21 of the conveyer 9 which, in turn, is run by a belt 22 on a pulley 23. 70

24 indicates a conduit leading from the fan which communicates with an opening 25 leading into the interior of the hull board 10.

In operation a blast of air will be continuously discharged from the elongated 75 opening 17 against the saw cylinder, and as the cotton, mixed with hull particles, in falling reaches the opening 26 between the mouth of the nozzle 16 and the saw cylinder the cotton will be blown by the blast of air 80 against the saw cylinder and be carried upward thereby, while the hulls will be permitted to fall and ultimately be discharged from the machine by the conveyer 9. The shoulder 15 prevents, as stated, the unopened 85 bolls and larger pieces of hull from passing into the space between the inclined portion 13 and the saw cylinder, said bolls and pieces of hull being knocked upward by the saw and ultimately passing between the crushing 90 roll 6 and the guard 7 whereby they are crushed and returned to the agitating chamber for separation from the cotton.

It will be seen from the above description 95 that the blast of air accomplishes the same purpose as that effected by the vibratory or reciprocating hull boards above referred to, and by regulating the blast of air a practically perfect separation of the hull particles and cotton can be obtained. By regulating the blast of air I mean having a blast of just sufficient force to insure that not only cotton particles, but also hull particles with cotton adhering thereto, shall be projected into contact with the saw cylinder. 100

I claim:

1. In a cotton extracting and cleaning machine, a saw cylinder, a hull board, the lower end of which defines the size of an opening 110 past the saw cylinder, and means for direct-

ing a blast of air from the hull board toward the saw cylinder.

2. In a cotton extracting and cleaning machine, a saw cylinder, a hull board, the lower end of which defines the size of an opening past the saw cylinder, and means for directing a blast of air from the lower end of the hull board toward the saw cylinder.

3. In a cotton extracting and cleaning machine, a saw cylinder, a hollow hull board having its lower end defining the size of an outlet past the saw cylinder and provided with an opening, and means for continuously forcing a blast of air into said hull board and through said opening.

4. In a cotton extracting and cleaning ma-

chine, a saw cylinder, a hollow hull board directed toward said saw cylinder and having its lower end portion inclined at a less angle thereto, said hull board being provided at its lower end with a discharge opening, and means for forcing air under pressure into said hull board whereby a blast of air will be directed through said opening toward the saw cylinder.

In testimony whereof, I have hereunto set my hand in presence of two subscribing witnesses.

BRUCE S. ELLIOTT.

Witnesses:

JOHN E. MITCHELL,
STELLA HILL.
